UNITED STATES PATENT OFFICE.

CHARLES HAMMER, OF BROOKLYN, NEW YORK, ASSIGNOR TO AMERICAN METAL CAP COMPANY, OF BROOKLYN, NEW YORK, A CORPORATION OF NEW YORK.

BOTTLE CAP OR SEAL.

1,027,330.

Specification of Letters Patent. Patented May 21, 1912.

Application filed April 8, 1911. Serial No. 618,741.

To all whom it may concern:

Be it known that I, CHARLES HAMMER, a citizen of the United States, residing at Brooklyn, in the county of Kings and State of New York, have invented new and useful Improvements in Bottle Caps or Seals, (Case A,) of which the following is a specification.

This invention relates to sheet-metal bottle caps or seals of that character having unpunched locking projections upon the flanges thereof to engage threads upon the mouth of the bottle or jar. In the manufacture of bottle caps of this type the use of very thin sheet-metal is desirable, first, on account of economy of material, whereby the caps may be manufactured and sold at less cost, and, second, because of the more ready response of thin metal to the action of the forming dies, whereby better shaped and more accurately-fitting caps may be made, a factor of importance in sealing the bottle or container tightly against evaporation or the ingress of air. There are disadvantages attendant upon the use of very thin metal, however, resulting from the tendency of the cap formed therefrom to bend or warp out of shape under pressures from handling, the drawing strain of the locking projections upon the flange from contact with the threads in applying the cap, and the gripping action of the thumb and fingers on the flange in both the applying and the removing operations. In the manufacture of caps of this character it is also desirable to provide a cap which will compensate for any inaccuracy of fit which would otherwise occur as a result of variations from the normal in the thickness of the tin plate or in the dimensions of the threads on the bottle neck due to defects in the forming mold.

The object of the present invention is to provide a simple form of cap which may be made of very thin sheet-metal and is yet strong and rigid enough to withstand all the imposed strains without bending out of shape, and which is at the same time adapted to compensate to some extent for variations from the normal in the dimensions and arrangement of the basal shoulder and threads upon the neck of the container.

The invention consists of the features of construction, combination and arrangement of parts, hereinafter fully described and

claimed, reference being had to the accompanying drawing, in which:

Figure 1 is a side elevation of the upper portion of a jar sealed by my improved cap. Fig. 2 is a bottom plan view of the cap removed. Fig. 3 is a vertical section through one side of the jar neck and cap on the line of one of the instruck locking projections. Fig. 4 is a vertical section through one side of the cap on a line between adjacent corrugations. Fig. 5 is a fragmentary vertical section through the cap looking toward the inner side of the flange thereof.

Referring to the drawing, the numeral 1 designates a neck of a bottle, jar or other similar container, the same being provided with external screw threads 2 and an annular shoulder 3 below the threads, against which shoulder the basal edge of the flange of the cap usually binds when the cap is fully applied.

The cap embodying my invention is formed of thin sheet metal and comprises a top 4 having a depending annular flange to inclose the neck 1 above the shoulder 3, said flange having an upper circular or truly cylindrical portion 5 and a bell-mouthed or outwardly and downwardly flared lower portion or skirt 6, the convex underside of the free edge of which is adapted ordinarily to bind against the shoulder 3 when the cap is fully applied. The portion 6, by being outwardly flared in the manner described into concavo-convex form by the action of a forming die, is stiffened and reinforced to a material extent, and yet is sufficiently resilient both vertically and transversely to yield or give when coming in contact with the shoulder 3, thus increasing the binding action of the cap upon the shoulder to more firmly retain the cap in applied position. This resilient action of the portion 6 also enables the application of caps to necks in which the thickness of the shoulder or its distance from the threads varies on account of any imperfections in the formation of the neck due to imperfections in the forming mold, such as the warping or shrinking of the mold from continued use. By this means an absolutely accurate fit of the cap upon the neck and the tight sealing of the container is insured under all conditions of service. The same action occurs where any variation in the

thickness of the metal prevails, as will be readily understood. The upper portion 5 of the flange is provided with a continuous series of corrugations or vertical bulges 7, 5 all of which are struck outwardly beyond the plane of such portion of the flange, in order that the corrugations will clear the threads 2 and will not bind upon the threads and prevent the free application of the cap 10 in the event that any imperfections or variations in dimensions occur in either the threads or cap under the conditions mentioned. These corrugations stiffen and strengthen the portion 5 and in addition form a milled 15 gripping surface whereby the cap may be firmly engaged in applying and removing. Immediately below the vertical corrugations the flared portion 6 is formed at intervals with instruck locking projections 8 to engage 20 the threads 2, whereby the cap is held and forced down upon the neck to effect a tight seal and to hold the usual liner or sealing disk 9 clamped against the rim edge of the neck. These locking projections, for 25 the sake of strength, are preferably made of triangular or semielliptical form and are arranged at the point of junction of the flange portions 5 and 6 and separated from the former by substantially horizontal slits 30 10, so that the upper edge 11 of the projection will extend inwardly and form a bearing surface to engage and bind against the under side of the thread. As shown, the projections are tangentially arranged, so 35 that the bearing edges 11 will incline in accordance with the degree of inclination of the threads. The described construction of the projections gives them great inherent strength to withstand the pressure imposed 40 in their engagement with the threads, and they are reinforced and additionally strengthened by the concavo-convex curvature of the skirt 6. By also arranging the upper portions of the projections at the 45 bases of adjacent corrugations 7, the walls of the projections are reinforced against the stanchion by the corrugations, whereby any tendency of the stanchions to become bent or deflected under their pressure on the 50 threads is prevented.

In the operation of applying and remov-

ing a cap, it will be understood that the projections are subjected to considerable force in riding up and down upon the threads, and tend to set up a downward pull 55 upon the flange sufficient, in a plane or unreinforced cap of thin metal, to bend or buckle the top of the cap and thus distort the cap out of shape and render it unfit for use. By reinforcing the cap in the manner 60 described, this objection is avoided, while at the same time a structure is produced which enables the cap to be made of thin sheet metal with a high degree of economy of manufacture and accuracy of fit upon normal containers, which cap is permitted by 65 the flexibility of the portion 6 to yield sufficiently without becoming distorted to accommodate itself to slight imperfections or variations which may exist in the thickness 70 of the metal or dimensions of the thread and shoulder.

Having thus described the invention, I claim:—

A sheet metal bottle cap having a circular 75 crown portion, and a flange depending therefrom and having a cylindrical upper half provided with an annular series of closely related outstruck vertical corrugations extending the full depth thereof and 80 having its lower half continuously flared outwardly and downwardly in pronounced bell-mouth form beyond the plane of said corrugations, said flared portion of the flange being provided with substantially semi-85 elliptical vertical instruck locking projections segmentally curved or bowed both longitudinally and transversely and having their major axes inclined at an angle to the normal perpendicular plane of the flange, the 90 upper edges of said projections being separated from the flange and inclined to the horizontal plane thereof and projecting inwardly beyond the vertical plane of the cylindrical portion of the flange. 95

In testimony whereof I affix my signature in presence of two witnesses.

CHARLES HAMMER.
